(57) **CLAIM**

I claim the ornamental design for a windshield deicer housing, as shown and described.

DESCRIPTION

FIG. 1. is a top perspective view showing my new design for a windshield deicer housing;

FIG. 2. is a bottom view thereof;

FIG. 3 is a left hand end view thereof;

FIG. 4 is a back view thereof;

FIG. 5 is a front view thereof;

FIG. 6 is a bottom view thereof; and,

FIG. 7 is a top view thereof.

The broken line structure is provided for purposes of environment and forms no part of the claimed design.

1 Claim, 5 Drawing Sheets
